UNITED STATES PATENT OFFICE.

ORA A. FERGUSON, OF TULSA, OKLAHOMA.

BURNER FOR GAS STOVES.

Application filed May 18, 1922, Serial No. 561,985. Renewed March 5, 1925.

To all whom it may concern:

Be it known that I, ORA A. FERGUSON, a citizen of the United States, resident of Tulsa, in the county of Tulsa and State of Oklahoma, have made a certain new and useful Invention in Burners for Gas Stoves; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a central vertical longitudinal section of the invention.

Figure 2 is a front view of the same.

Figure 3 is a transverse section of the same taken vertically through one of the 20 burner tubes.

Figure 4 is a detail perspective view of a modified form of burner tube.

Figure 5 is a detail vertical section of the same.

25 Figure 6 is a central vertical longitudinal section of a modified form of the invention showing parts in full lines.

Figure 7 is a central vertical transverse section of the same.

30 Figure 8 is a detail central longitudinal vertical section of the top member of the invention.

The invention has relation to burners for 35 gas stoves, of the Bunsen type, having for an object certain improvements therein designed to increase the efficiency and durability of the burner. Other objects and advantages will appear.

40 The invention consists in the novel construction and combination of parts, as hereinafter set forth.

In the accompanying drawings illustrating the invention, the numeral 1 designates the horizontally elongated body of the 45 burner composed of an upper section 2 and a lower base section 3 the latter being of trough form, and having in the plane of its upper edge a horizontal central partition or baffle 4, dividing the chamber of said body into upper and lower horizontal 50 passages 6 and 7, the upper passage being closed at one end at 5 and the horizontal partition terminating short of the opposite end of the chamber of the said body, whereby the said passages 6 and 7 communicate with each other at one end thereof at 7.

The base trough section is of semi-circular form in cross section, as is also the upper or cover section, the burner being as a whole of circular form in cross section, the baffle 60 being diametric thereof and the cover section having its lower edge in the plane of said baffle.

The body of the burner is provided at its forward end with an annular flaring head 65 or extension 8, usually formed as an integral part of said base section and of said baffle and provided at its outer end with a valve 9 whereby more or less air may be admitted thereto, the said flaring head communicat- 70 ing at its inner contracted end with the forward end of the lower passage 7.

In practice it is designed that the lower section 3 shall have a plurality of lateral perforated lugs 10 adapted to receive thereupon the matching perforated lugs 11 of the upper or cover section 2, bolts 11^a connecting the lugs and thereby holding the two sections of the burner together to form a 75 unitary burner. The end of the burner opposite the air and gas admission end or forward end thereof may be formed with upper and lower oppositely tapering or inclined walls 12 and 13, whereby the gas which is admitted to the central opening 14 of the flaring head 8 of the burner by suitable means, and which gas travels longitudinally of the burner along the lower chamber 7, will be guided upwardly into the upper chamber 6, thereby increasing the 80 efficiency of the burner.

The lower chamber 7 is usually provided with an opening in its bottom at 16 near the gas and air admission head 8, said opening being designed to admit a small amount of air to admix with the gas, even when the valve 9 is closed.

Communicating with the upper chamber 6 of the burner are a plurality of burner tubes 17 which may be of square or round 100 cross section and are joined to the top wall of the upper section of the burner. These burner tubes are vertical and may be formed with suitable outlet openings for the gas, either by means of kerfs 18 formed by disk saws entering the closed upper ends of said burner tubes and penetrating said ends or tops as shown in Figures 1 and 2, or by means of straight edge saws or hack saws penetrating also partly the sides of the 105 upper ends of the tubes as shown in Figures 4 and 5.

2
The burner tubes are made of square cross section when tubes of refractory material capable of being rendered incandescent are to be placed thereover, and of round cross section when to be used with asbestos back gas heating stoves.

The burner tubes may be provided with gas outlet openings of other nature than that described if desired.

10 The gas and air admitted to the end of the burner body will thoroughly admix together before being delivered to the upper chamber 6 owing to passage longitudinally the full length of the burner through the 15 lower chamber 7 before being delivered to said upper chamber, and as the mixture of gas and air is delivered to the said upper chamber in a longitudinal current, the upward flow of the mixture of air and 20 gas into and out of the burner tubes will be at a lesser speed and with a better admixture than would otherwise be the case, whereby fuming of the gas and blowing off of the tops of said tubes will be prevented 25 and the gas burned more evenly and economically and with better heating effect or efficiency.

In Figures 6 and 7 of the drawings a modification of the invention is shown 30 wherein the lower section of the body of the burner is closed at both ends and is provided with a central depending tubular extension—adapted for admission of air and gas at its free end or head—this form of 35 the invention being designed for use with gas heaters to be used in fireplaces.

In both forms of the invention the upper

section of the burner body remains the same, but the lower sections are interchangeable as may be required.

40 I claim:

1. A gas burner, comprising a base trough section of semi-circular form in cross section and having a baffle integral therewith and in the plane of its upper edge and 45 a gas inlet port, and a cover section also of semi-circular form in cross section and having its lower edge in the plane of said baffle and being provided with burner tips, said cover section being of the same length 50 of said base section and forming therewith a burner of circular form in cross section, of which said baffle is diametric.

2. A gas burner, comprising a base trough section of semi-circular form in cross section and having a baffle integral therewith and in the plane of its upper edge, and a cover section also of semi-circular form in cross section and having its lower edge in the plane of said baffle and being provided 55 with burner tips, said cover section being of the same length as said base section and forming therewith a burner of circular form 60 in cross section of which said baffle is diametric, said base section having a gas inlet portion extension of one end thereof integral therewith and with said baffle.

65 In testimony whereof I affix my signature in presence of two witnesses.

ORA A. FERGUSON.

Witnesses:

T. D. JONES,

M. G. JONES.
